UNDERREAMER

Emmett J. Roe, Wichita, Kans., assignor of
one-half to C. E. Glamann

Application May 14, 1934, Serial No. 725,603

22 Claims. (Cl. 255—76)

My invention relates to underreamers for enlarging or reaming well holes and is an improvement over the type of underreamer disclosed in my application filed March 25, 1933, Serial Number 662,764.

- It is an object of the present invention to provide an underreamer having pivotally mounted cutters, operable to expand into cutting engagement with the walls of the well hole and adapted to start cutting without the necessity of raising the well casing, the cutters being capable of maximum expansion, so as to materially increase the diameter of the well hole and thereby increase the oil production capacity of the well.
- A further object of the invention resides in pivotally mounting the cutters in the reamer body to permit maximum expansion and contraction of the cutters and providing operating means for exerting a constant tension on the cutters to rock them into expanded position.

A still further object of the invention resides in providing a plurality of different types of cutters capable of varying degrees of expansion, the cutters being mounted in the reamer body so as to be readily interchangeable, and thus permit the hole to be reamed to the desired size.

Another object of the invention is to provide an underreamer of the above-mentioned character which is simple and durable in construction, reliable and efficient in operation and inexpensive to manufacture.

Other objects and advantages of the invention will be apparent during the course of the following description.

In the accompanying drawings, forming a part of this specification and in which like numerals are employed to designate like parts throughout the same,

Fig. 1 is a longitudinal sectional view of the reamer showing the cutters in collapsed position while being passed through the well casing,

Fig. 2 is a side elevation view of the reamer,

Fig. 3 is a view similar to Fig. 1, showing the reamer below the end of the well casing with the cutters fully expanded,

Fig. 4 is a longitudinal sectional view of the reamer showing a modified form of cutter in collapsed position,

Fig. 5 is a similar view, showing still another form of cutter in fully expanded position,

Fig. 6 is a cross section taken on line 6—6 of Fig. 1,

Fig. 7 is a cross section taken on line 7—7 of Fig. 4, and,

Fig. 3 is a cross section taken on line 8—8 of Fig. 5.

In the drawings, wherein for the purpose of illustration, I have shown a preferred embodiment of the invention, the numeral 5, denotes the body of the reamer. Its lower end is wedge shaped with opposed tapered faces 6. The faces 6 and sides of the body contiguous therewith are provided with opposed longitudinal grooves or sockets 7, in which the reamer cutters 8 are pivotally mounted, in the upper ends thereof. The upper ends of the sockets are separated by the dividing wall 9, which forms the bottom wall of the sockets and terminates at its lower end above the lowermost ends of the cutters. Wall 9 has a central longitudinal slot 10, extending throughout its entire length to receive the cross bar 11 which extends through the transverse opening 12 in the lower end of the plunger 13. The plunger 13 is mounted to reciprocate in the central longitudinal bore 14 of the body 5. Bore 14 communicates with the slot 10, and its upper end is enlarged, as at 15, to receive the expandable coil spring 16, which is mounted on the plunger and exerts a constant upward tension thereon. The ends of the cross bar 11 extend into the transverse openings 17 in the cutters, and the lower edge of the cross bar midway its length is provided with a notch 18 which engages the lower edge of the opening 12 and secures the cross bar against accidental displacement. The inner faces or back of the cutters 8, at their upper ends, are provided with spaced lugs 19, which are seated in spaced recesses 20 formed in the bottom wall of the sockets, at their upper ends, and serve as a fulcrum for the cutters to permit pivotal movement of the cutters into and out of the sockets. The inner ends of the openings 17 are relatively wider vertically than the cross bar to permit pivotal movement of the cutters and when the cutters are collapsed the upper edge of the cross bar, at its ends, contacts with the top wall of the openings 17, and through the action of the spring 16, which exerts an upward pull on the plunger 13, the cross bar is caused to rock the cutters on their fulcrums, until fully expanded, as shown in Fig. 3. The top ends of the cutters are obliquely cut, as at 21, which abut against the upper ends 22 of the sockets, which are inclined downwardly at an angle to the axis of the body, when the cutters are fully expanded. The outer faces of the cutters are curved transversely to conform to the curvature of the well hole and reamer body, the lower portions being inclined outwardly to provide projecting cutting edges 23, 55

at their lower ends. The sides of the cutters adjacent their inner faces are provided with laterally extending longitudinal flanges 24, adapted to contact at their lower ends with the flanges 25 along the sides of the sockets when the cutters are expanded. The lower ends of the cutters, at their inner faces, are provided with depending legs 26, adapted to abut when the cutters are collapsed. The lower ends of the sockets 10 have a central web 27, in alignment with the dividing wall 9, and attached to opposite sides of the web are angle brackets 28, secured in place by a bolt 29, passing through one of the apertures 30 in the web. There is a series of apertures 30 in vertical alignment, to permit vertical adjustment of the brackets with respect to the lower ends of the cutters. The horizontal arms 31 of the brackets are disposed beneath the lower ends of the cutters 8 and have upturned hooks 32 20 at their outer ends which are engaged by the legs 26 of the cutters, when the cutters are fully expanded. The arms 31 are the same width as the sockets, their outer corners being rabbeted, as at 33, to receive the flanges 25 of the sockets. Thus, it is seen that the brackets 28 close the sockets at a point below the lower end of the cutters and prevent the cutters from accidentally dropping from the sockets. The arms 31 of each bracket each have a series of openings 34, there- 30 through to prevent a sand trap from forming in the sockets. When passing the reamer through the well casing 35, the cutters are secured in collapsed position by tying with a string or other suitable manner.

In Figs. 1, 2, and 3, the type of cutters shown are employed during the initial reaming operation, and in Figs. 4 and 5, modified types of cutters are shown which are designed to permit greater expansion. The cutters 36 in Fig. 4, differ from the cutters 8, in that the body is thicker, so that their outer faces 37, ride against the walls of the casing 35, when the reamer is passed through the casing. The outer faces of the cutters, at their lower ends, are slightly inclined inwardly, as at 38, to provide cutting edges 39, which do not contact with the casing when the cutters are collapsed. Also the legs 40, depending from the bottoms of the cutters, are off-set as at 41, to extend beyond the longitudinal axis of the reamer body and each leg is cut-out, as at 42, 45 so that the legs may overlap, which permits greater contraction of the cutters to make allowance for the increased thickness of the cutter body. By off-setting the legs 40, shortening the length of the flanges 43 on the cutters and increasing the angle of the upper ends 44, the cutters are made capable of greater expansion. In Fig. 5, a type of cutter 45 is shown which is designed for still greater expansion. This type of cutter differs from the cutters 36, in that the legs 46 are off-set to a greater extent, so as to extend beyond the longitudinal axis of the reamer body when the cutters are collapsed and by reducing the length of the flanges 47 on the cutters and increasing the angle of the upper ends 48, it will be seen the cutters are permitted to expand to a maximum degree. When the cutters 45 are used the brackets 28 are lowered to make allowance for the greater length of the legs 46.

In use, the type of cutters 8, shown in Figs. 1 to 3 inclusive are first employed in starting the reaming operation and when the reamer is passed through the well casing 35 the cutters are tied in collapsed position with a piece of string which will break when the cutters pass the lower end of

the casing and the reaming operation commences. When the cutters are released the tension of the coil spring 16 on the plunger 13 causes the cross bar 11 to rock the cutters on their fulcrums 19, so as to swing the cutters out of their sockets 5 1, thus moving the cutting edges 23 into working engagement with the walls of the well hole. As shown in Fig. 3, the cutters when fully expanded will have their upper ends 21 in contact with the ends 22 of the sockets, the cutter flanges 24 will 10 be in contact with the flanges 25 of the sockets and the legs 26 will be in contact with the upturned hooks 32 of the brackets 28, which three points of contact control the expansion of the cutters. After the initial reaming operation, the 15 reamer is withdrawn from the well and the type of cutters 36, shown in Fig. 4, are substituted for the cutters 8. These cutters are so designed that their outer faces 37 ride against the walls of the casing 35, permitting the reamer to be passed through the casing without having to tie the cutters in collapsed position. By off-setting the legs 40, shortening the flanges 43, and increasing the angle of the upper ends 44 of the cutters 36, they are made capable of greater expansion and thus, 25 increase the diameter of the well hole. By substituting the type of cutters 45, shown in Fig. 5, a maximum expansion of the cutters is possible, making it possible to increase the diameter of a six inch well hole to as much as fifteen inches. 30 Thus, it is seen by using various types of cutters, the diameter of the well may be increased as desired to control the oil production capacity of the well. The cutters are so mounted in the sockets, as to be easily removed, thereby permitting the various types of cutters to be interchanged as the reaming operation progresses. To remove the cutters, the brackets 28 are first removed and then the plunger 13 is depressed with a suitable tool provided for the purpose, 40 moving the cutters into the lower ends of the sockets below the flanges 25, where they may be taken off of the cross bar and removed from the sockets.

It is to be understood that the form of my invention herewith shown and described is to be taken as a preferred example of the same and that certain changes in the shape, size and arrangement of the parts may be made without departing from the spirit of the invention or the 50 scope of the subjoined claims.

Having thus described my invention, I claim:—

1. In an underreamer, the combination of a reamer body having sockets, cutters fulcrumed at their upper ends in said sockets and means 55 for exerting an upward pull on said cutters to support and rock the cutters on their fulcrums to operative position.

2. In an underreamer, the combination of a reamer body having sockets, cutters fulcrumed at their upper ends in said sockets, a cross bar extending through a slot in the bottom of said sockets having its ends loosely disposed in openings through said cutters, and tensioning means for actuating said cross bar to expand said cutters to operative position.

3. In an underreamer, the combination of a reamer body having longitudinal sockets, cutters fulcrumed at their upper ends in said sockets having oblique upper ends adapted to abut 70 against the upper ends of the said sockets when the cutters are expanded and means for exerting an upward pull on said cutters to support and rock the cutters on their fulcrums to operative position.

4. In an underreamer, the combination of a reamer body having opposed sockets, cutters fulcrumed at their upper ends in said sockets for movement in and out of said sockets, a cross bar extending through a slot in the bottom of said sockets having its ends loosely disposed in openings through said cutters, a plunger slidably mounted in said reamer body having its lower end connected with said cross bar, and means for exerting a constant upward pull on said plunger, whereby said cutters are rocked by said cross bar to an expanded position. 5
5. In an underreamer, the combination of a reamer body having opposed sockets, cutters fulcrumed at their upper ends in said sockets, legs depending from the lower end of said cutters, means for expanding said cutters, and removable means engageable with said legs when said cutters are fully expanded. 10
6. In an underreamer, the combination of a reamer body having opposed sockets, cutters fulcrumed in said sockets, legs depending from the lower end of said cutters, means for expanding said cutters, and brackets mounted in said sockets beneath said cutters adapted to be contacted by said legs when the cutters are fully expanded. 15
7. In an underreamer, the combination of a reamer body having opposed sockets, cutters fulcrumed at their upper ends in said sockets, legs depending from the lower end of said cutters, means for expanding said cutters, and removable means closing said sockets below said cutters having hooks engageable with said legs when the cutters are fully expanded. 20
8. In an underreamer, the combination of a reamer body having opposed sockets, cutters fulcrumed in said sockets, legs depending from the lower end of said cutters, said legs being off-set and adapted to overlap when the cutters are collapsed, means for expanding said cutters and means engageable with said legs when the cutters are fully expanded. 25
9. In an underreamer, the combination of a reamer body having sockets, cutters fulcrumed at their upper ends in said sockets, a cross bar supporting and loosely connecting said cutters and means for actuating said cross bar to swing said cutters on their fulcrums to expanded operative position. 30
10. In an underreamer, the combination of a reamer body having opposed sockets, cutters fulcrumed at their upper ends in said sockets having transverse openings therethrough, a cross bar having its ends loosely disposed in the openings of said cutters below their fulcrum points and means for raising said cross bar to swing said cutters on their fulcrums to expanded operative position. 35
11. In an underreamer, the combination of a reamer body having sockets, cutters fulcrumed at their upper ends in said sockets having oblique upper ends adapted to abut against the upper ends of said sockets when the cutters are expanded, a cross bar loosely connecting said cutters below their fulcrum points and means for actuating said cross bar to swing said cutters on their fulcrums to expanded operative position. 40
12. In an underreamer, the combination of a reamer body having opposed sockets, cutters in said sockets having lugs projecting from their inner face adapted to fulcrum in recesses formed in the base of the sockets, and means for supporting and swinging said cutters on their fulcrums into expanded operative position. 45
13. In an underreamer, the combination of a reamer body having opposed sockets, cutters in said sockets having lugs projecting from their inner face adapted to fulcrum in recesses formed in the base of the sockets, means loosely supporting said cutters in said sockets, and means for actuating said first mentioned means to swing said cutters on their fulcrums into expanded operative position. 50
14. In an underreamer, the combination of a reamer body having opposed sockets, cutters in said sockets having lugs projecting from their inner face at their upper ends adapted to fulcrum in recesses formed in the base of the sockets, a cross bar having its ends loosely disposed in openings in said cutters below their fulcrum points, and means for actuating said cross bar to swing said cutters on their fulcrums into expanded operative position, the upper ends of said cutters being adapted to abut against the upper ends of said sockets, to limit the expanding of the cutters. 55
15. In an underreamer, the combination of a reamer body having sockets, cutters fulcrumed at their upper ends in said sockets, means below the fulcrum points of said cutters connecting and supporting the cutters and means for pulling said first mentioned means upwardly to expand the cutters to operative position. 60
16. In an underreamer, the combination of a reamer body having sockets, cutters fulcrumed in said sockets and means below the fulcrum points of said cutters for exerting an upward pull on said cutters to rock the cutters on their fulcrums to expanded position. 65
17. In an underreamer, the combination of a reamer body having sockets, cutters fulcrumed in said sockets, means below the fulcrum points of said cutters having connection with said cutters adjacent their outer faces, and means for pulling said first mentioned means upwardly to rock said cutters on their fulcrums to an operative position. 70
18. In an underreamer, the combination of a reamer body having sockets, cutters fulcrumed in said sockets and means for rocking said cutters on their fulcrums to expanded position including a cross bar having bearing engagement with the cutters at points below and to one side of the fulcrum points. 75
19. In an underreamer, the combination of a reamer body having sockets, cutters fulcrumed in said sockets and means for rocking said cutters on their fulcrums to expanded position including a cross bar having its ends loosely disposed in openings in said cutters below their fulcrum points, the ends of said bar having bearing engagement with said openings on one side of the fulcrum points of the cutters. 80
20. In an underreamer, the combination of a reamer body having sockets, cutters fulcrumed in said sockets and means for rocking said cutters on their fulcrums to expanded operative position including a cross bar below the fulcrum points of the cutters having its ends loosely disposed in openings in said cutters, the ends of said bars having bearing engagement with the top of said openings past the longitudinal axis of said cutters. 85
21. In an underreamer, the combination of a reamer body having sockets, cutters fulcrumed at their upper inner sides in said sockets, and means for rocking said cutters on their fulcrums to expanded operative position including a cross bar having its ends loosely disposed in openings intermediate the ends of said cutters, the ends of said cross bar having bearing engagement with 90

the top of said openings at points beyond the longitudinal axis of said cutters.

22. In an underreamer, the combination of a reamer body having sockets, cutters fulcrumed at their upper inner sides in said sockets, a cross bar extending between said cutters below their fulcrums having its ends loosely disposed in openings through said cutters, the ends of said bar

having bearing engagement with the top of said openings at points beyond the longitudinal axis of said cutters and tensioning means connected with said cross bar for exerting an upward pull on the cross bar whereby said cutters are rocked on their fulcrums to expanded position.
